UNITED STATES PATENT OFFICE.

HARRY VISSERING, OF ST. LOUIS, MISSOURI, ASSIGNOR TO THE WESTERN RAILWAY EQUIPMENT COMPANY, OF EAST ST. LOUIS, ILLINOIS.

DESIGN FOR A DRAFT-LUG AND DRAW-BAR FOLLOWER.

SPECIFICATION forming part of Design No. 26,941, dated April 20, 1897.

Application filed February 5, 1897. Serial No. 622,226. Term of patent 14 years.

To all whom it may concern:

Be it known that I, HARRY VISSERING, a citizen of the United States, residing at the city of St. Louis, State of Missouri, have invented a certain new and original Design for a Draft-Lug and Draw-Bar Follower, of which the following is a full, clear, and exact description, reference being had to the accompanying drawings, wherein—

10 Figure 1 is a perspective view of a draft-lug and draw-bar follower embodying my new and original design as seen from the rear and below. Fig. 2 is a perspective view as seen from the front and above.

15 This invention relates to a new and original design for a draft-lug and draw-bar follower; and it consists in the shape and configuration thereof, as will hereinafter be more fully described.

20 In the drawings, A indicates the front wall, which is formed with a circular opening *a* about its middle. Forwardly-extending projections *a'* are arranged on each side of said opening, and a curved projection *a''* is formed 25 on the lower edge of said front wall.

B indicates the side walls, which are formed with ribs *b* and *b'*, running vertically the entire height of said walls. Between these ribs *b* and *b'* are circular openings. The inner 30 faces of the side walls are formed with ver-

tically and horizontally disposed raised ribs which intersect each other near the rear end, as shown. The rear end is open.

C indicates the top wall, formed with a triangular-shaped opening, and D indicates the 35 bottom wall, formed with a similarly-shaped opening, said openings leaving strips *c* and *d*, which extend across the end of the structure at the top and bottom thereof.

The curved lower edge of the front wall 40 forms the cross of a T-shaped projection, which is formed on the front edge of the bottom wall, as shown in Fig. 1.

I am aware of the Design Patent No. 25,957, granted to Andrew G. Steinbrenner for a similar device. The Steinbrenner design does not have the cross-strips *c* and *d*, which distinguish my draft-lug and draw-bar follower from any with which I am familiar.

What I claim is—

The herein-described design for a draft-lug and draw-bar follower, substantially as shown and described.

In testimony whereof I hereunto affix my signature, in presence of two witnesses, this 55 1st day of February, 1897.

HARRY VISSERING.
